Patented Jan. 20, 1914.

UNITED STATES PATENT OFFICE.

JOHN B. OLESON, OF FORT ATKINSON, WISCONSIN.

STANCHION.

1,084,816.

Specification of Letters Patent.

Patented Jan. 20, 1914.

Application filed October 3, 1912. Serial No. 723,772.

To all whom it may concern:

Be it known that I, JOHN B. OLESON, a citizen of the United States, residing at Fort Atkinson, in the county of Jefferson and 5 State of Wisconsin, have invented a new and useful Stanchion, of which the following is a specification.

The present invention relates to improvements in stanchions.

10 The primary object of this invention is the provision of a novel form of means for swivelly supporting the stanchion both at its lower and upper ends, the upper end being in the form of a lock which will permit 15 of the rotation of the stanchion without affecting the locking and releasing mechanism thereof.

A further object of the present invention is a construction of stanchion and lock 20 therefor which simplifies the method of captivating the animal, and of releasing the same, there being provided a single swinging member having means for engaging the lock, the locking bolt for engaging the same 25 remaining in the same relative position to the swinging member regardless of the position of the stanchion.

With the foregoing and other objects in view which will appear as the description 30 proceeds, the invention resides in the combination and arrangement of parts and in the details of construction hereinafter described and claimed, it being understood that changes in the precise embodiment of the 35 invention herein disclosed can be made within the scope of what is claimed without departing from the spirit of the invention.

In the drawings Figure 1 is an elevation 40 of the complete stanchion with the present invention applied thereto, Fig. 2 is an elevation and partial section of the casing with one section removed showing the portion carried by the stationary stanchion member and the portion carried by the swinging 45 member in locked relation. Fig. 3 is an enlarged detail view of the locking bolt and actuating mechanism. Fig. 4 is a top plan view of the lever for actuating the bolt. Fig. 5 is a bottom plan view of the locking bolt. Fig. 6 is a view similar to Fig. 2 taken 50 at right angles thereto.

Referring to the drawings, the numeral 1 designates the lower or swivel connection

for the stanchion with the floor while 2 designates the stanchion carrying bar which 55 is disposed above and parallel to the floor. The stanchion consists of the relatively stationary member 3 and the pivoted member 4. Connected to and carried by the upper end of the stationary member 3, are two 60 castings 5, which are so formed as to embrace the upper end of the member 3 and be secured thereto, each casting being provided with outwardly extending arms 6, which when assembled constitute a guiding yoke 65 for the locking end 16 of the swinging member 4. These castings 5 when assembled form a circular boss 7 having the central bore 8 with a reduced portion 27, the purpose of which will presently appear. The 70 annular rim or flange 9 with its boss 7, rotatably fits in the aperture 10, formed by the reinforced portion of the sections 11 of the casing supported fixedly from the bar 2.

The sections 11 of the lock carrying casting 75 and that portion forming the female connection of the swivel joint are held together by means of the bolts 12, and in the upper portion of said sections, is formed the longitudinal sleeve 13 which provides a 80 channel for the bar 2 and upon which the sections 11 are clamped. Secured in the upper end of the swinging member 4 is a boss 17 of the locking member 16, the same being so positioned as at all times when moved 85 toward the locking sections 11 to pass between the forked ends 6 and into the socket formed in the end of the castings 5, there to engage the reduced end 15 of the locking bolt 14, all as clearly illustrated in Fig. 2. 90

In order to properly actuate the locking bolt 14 to release the swinging member 4, when desired, an integral stud 19 carried by the locking bolt 14 and provided with the reduced stem 20 and head 21, is fitted within 95 the forked end 23 of the pivoted bolt actuating lever or arm 22, the same being mounted upon one of the bolts 12 and held downwardly and resiliently by means of the spring 25, whose terminal or bail 26 engages 100 the forked end 23 of the arm or lever 22. The coils of the spring 25 are wound upon the bolt 12, as clearly shown in Figs. 2 and 3.

To insure the rotation of the locking bolt 14 with the swivel joint, so that the locking 105 end 15 will always be in position to engage

the locking end 16 of the swinging member 4, the rib 18 is formed integral with the locking bolt 14 and is seated slidably within the recessed portion 27 of the two castings 5 5, the same forming in a reality a key and key way, respectively.

In order to release the locking bolt 14, to permit of the swinging member 4 being disengaged from the stationary member 3, the 10 bail 28 is journaled within the respective sections 11 of the lock casing, and is provided with the exteriorly disposed handle 29 which when moved to the right as viewed in Fig. 1, will elevate the lever 22 and consequently 15 retract the bolt 14 so that its locking end 15 will be disengaged from the locking head 16 of the member 4. An off set handle 30 is carried by the handle 29 to form a ready means for manipulating the same 20 to release the animal.

The swivel connection 1, is identical with that shown in the present applicant's U. S. Letters Patent No. 1,001,071, and in connection with the present device is readily 25 adaptable.

From the foregoing description, taken in connection with the drawings, it is evident that with a stanchion constructed according to and embodying the present invention, 30 that the swinging member 4 is quickly locked and from any direction, regardless of the position thereof, as the locking bolt 14 will always be in the proper position. Also that by reason of the handle 29, the locking bolt is readily released to permit the swinging member 4 to fall and release the animal. By constructing the locking head 16 as shown, the handle 29 does not have to be manipulated when the stanchion is placed 35 about the neck of the animal.

What is claimed is:

1. The combination with a two-membered stanchion, of a support and locking device for the upper ends thereof, including a sectional casing having a reduced opened lower end, a hollow boss carried by one member of the stanchion and rotatably mounted in the open end of the casing, a bolt vertically 45 slideable within the boss, a bolt engaging portion carried by one end of the other member of the stanchion, a spring actuated lever disposed within the casing and operably connected to the bolt, and means mounted in the casing and operable exteriorly thereof for retracting the lever and bolt against the spring.

2. The combination with a two-membered stanchion, of a support and locking device for the upper free ends thereof, including a 60 vertically separated two-part casing, the upper portion of which is a support engaging portion while the lower portion is a lock containing portion and is provided with a vertically disposed circular aperture, a flanged boss projecting through the

aperture and mounted for rotation within the casing, said boss being provided with an irregular shaped opening therethrough, a bolt fitting in said irregular shaped opening and held against rotation thereby, said bolt being provided with a reduced and headed upper end disposed within the casing, a spring actuated lever mounted in the casing and engaging the reduced upper end of the bolt to project the lower end of the bolt into locking position, a stanchion member engaging portion carried by the boss, a locking member carried by the free end of the other stanchion member, and a lever actuated crank arm mounted in the casing 80 for operating the lever to retract the bolt against the spring.

3. A support and locking device for the upper ends of the stanchion members, including a two-part casing provided with an opening through the lower end thereof, a stanchion member engaging portion provided with an apertured boss rotatably mounted in said opening of the casing, the aperture of the boss being irregular shaped 90 and extending the full length of the boss, a vertically slideable bolt mounted in said irregular shaped aperture of the boss and conforming in shape to said aperture, said bolt being provided with a reduced and headed portion projecting concentrically above the boss within the casing, the lower end of said bolt being the locking end, a lever pivoted within the casing and provided with a slotted end disposed to straddle and engage the reduced end of the bolt below the head thereof, a spring mounted in the casing and engaging the lever to normally hold the bolt projected, and a lever actuated crank journaled in the casing and 100 disposed to engage the lever to retract the same and the bolt against the spring.

4. A support and locking device for the upper ends of two stanchion members, including a two-part casing provided with an opening through the lower end thereof, a stanchion member engaging portion provided with an apertured boss rotatably mounted in said opening of the casing, the aperture of the boss being irregular shaped 110 and extending the full length thereof, a vertically slideable bolt having a portion corresponding to the irregular shaped aperture of the boss mounted therein for sliding movement, said bolt having a reduced cylindrical portion extending from one end thereof into the casing, said cylindrical portion being further reduced and terminating in a flat head, a lever pivoted within the casing and provided with a slotted terminal, 115 a portion of which is enlarged to receive the reduced portion of the bolt below the flat head, a spring mounted in the casing and engaging the free slotted end of the lever to hold the bolt projected with its lower 120 130

locking end within the stanchion member
engaging portion, and a lever actuated
crank journaled transversely of the casing
and disposed to engage the under-side of the
lever upon the opposite side of the bolt
to the slotted terminal.

In testimony that I claim the foregoing as

my own, I have hereto affixed my signature
in the presence of two witnesses.

JOHN B. OLESON.
